B. A. Wheeler

Attorney

UNITED STATES PATENT OFFICE.

PAUL LESNESKY, OF DETROIT, MICHIGAN.

LOOM PLATE FOR ELECTRIC FIXTURES.

Application filed June 12, 1922. Serial No. 567,728.

To all whom it may concern:

Be it known that I, PAUL LESNESKY, a citizen of the United States, residing at Detroit, in the county of Wayne and State of Michigan, have invented a new and useful Loom Plate for Electric Fixtures, of which the following is a specification.

This invention relates to loom plates for supporting electric fixtures.

10 The object of the invention is to provide a loom plate and mounting therefor adapted to be supported by the floor joists of a building and to form a hanger for supporting an electric fixture, and in which the formulation and association of the parts is such as to permit of rapid assembly in an interlocking relation so as to provide for adjustment of the plate longitudinally of the mounting and also for the retention of the parts in 15 the desired position of adjustment without necessitating the employment of bolts, set screws or similar tensioning members.

A preferred embodiment of the invention is illustrated in the accompanying drawings, 20 in which,

Fig. 1 is a bottom view of the loom plate and its mounting indicating by dashed lines the joists supporting the same.

Fig. 2 is a side elevation view of the parts 25 shown in Fig. 1.

Fig. 3 is an enlarged longitudinal sectional view taken on line 3—3 of Fig. 1.

Fig. 4 is a cross-sectional view taken on line 4—4 of Fig. 1.

35 In these views the reference character 1 indicates a peripherally flanged loom plate having the usual circular series of plugged loom openings 2. The plate 1 centrally carries a depending stud bolt 3, the shank there-

40 of passing through an opening 4 in the plate, and having its head 5 seating on top of the plate. Said head engages in a channel shaped depression 6 formed in the face of the plate and has beveled edges 5' registering with the sides of said depression to prevent turning of the bolt. The plate is carried by a bar 7, preferably of metal rectangular in form, which bar is adapted to span adjacent joists 8 and is formed terminally with screw or nail holes 9 adapting it to be fastened to said joists.

50 The mounting of the loom plate upon the bar 7 is effected by a bridge member 10,

preferably stamped from sheet-metal, said member having arched end portions 10' embracing the bar, which are riveted at their extremities to the plate 1 at opposite sides of the center upon the outer face thereof and a connecting strip 10'' which is downwardly bowed to bear firmly upon the upper face of said bar. The stud 3 has its top face grooved to receive the lower face of said bar, as is clearly seen in Fig. 4, and thus the bar holds the stud against rotation and additionally prevents any upward shifting of the stud from its proper position as shown. Any shifting of the loom plate lengthwise upon the bar 7 is resisted by the frictional engagement of the bar between the stud head 5 and the member 10. The resistance to such movement, however, is so predetermined as to permit such adjustment of the plate upon the bar as may be necessary to properly install the device. It is to be understood that the stud 3 is adapted for engagement by any suitable electric fixture (not shown) for lights or other purposes, such as is commonly supported from walls or ceilings.

55 It is a distinctive feature of the described invention that proper positioning of the loom plate upon its supporting bar is accomplished without manipulation of any nuts or screws, and also that the desired rigid relation between the stud bolt 3 and the loom plate is established without such manipulation. Furthermore these results are obtained without especially machining or otherwise fashioning the rectangular supporting bar.

60 What I claim is:

1. The combination with a supporting bar, of a loom plate, and a bridge member having arched extremities embracing said bar and rigidly secured to said plate, said bridge having a deflected portion engaging the bar and frictionally resisting movement of said plate longitudinally of said bar.

65 2. The combination with a supporting bar, of a loom plate, a bridge member having arched extremities embracing said bar and secured to said plate, said bridge having a deflected intermediate portion frictionally engaging said bar, and a fixture support extending through the loom plate and having a head portion interposed be-

tween said bar and plate and co-acting with said bridge to frictionally resist movement of said plate along said bar.

3. The combination with a supporting bar, of a loom plate, a bridge member having its extremities secured to said plate and intermediately deflected to engage said bar and a fixture support extending through

said plate and having a head between said bar and plate recessed to receive said bar, 10 said head co-acting with said bridge to frictionally restrain said members against relative movement.

In testimony whereof I sign this specification.

PAUL LESNESKY
